Manufacturing Company, Rochester, N. Y., a
corporation of New York

Application September 14, 1939, Serial No. 294,874

4 Claims. (Cl. 20—69)

This invention relates to weather strips, and, more especially, to the variety thereof commonly known as a windlace and employed for sealing the crevices and joints of windows and doors of structures and the like, against the passage of dust and the weather.

One object of the invention is the provision of a more improved and efficient windlace comprising a body portion and an attaching flange so constructed as to afford high and permanent resilience in the flange for maintaining the body portion in sealing position.

Another object is the provision of a flexible, unitary windlace of the above character in which the attaching flange is longitudinally resilient, so that the body portion may be bent smoothly and uninterruptedly around corners or curved sides of a door or window, with the flange attached in flat and neat condition to the support.

To these and other ends the invention resides in certain improvements and combinations of parts, all as will be hereinafter more fully described, the novel features being pointed out in the claims at the end of the specification.

In the drawing:

Fig. 1 is a sectional view showing a door and door frame joint having applied thereto a windlace embodying one form of the present invention;

Fig. 2 is a view of the parts shown in Fig. 1 as seen from above;

Fig. 3 is an enlarged sectional view through another form of windlace embodying the present invention, and

Fig. 4 is a similar view of a modified form.

The same reference numerals throughout the several views indicate the same parts.

This invention is in the nature of an improvement upon the windlace disclosed in United States Letters Patent to Charles P. Schlegel, No. 2,103,697, dated December 28, 1937. Weather stripping and method of making the same, and is herein disclosed, by way of illustration, in several forms, as applied to the sealing of a door of an automobile body. Referring more particularly to the drawing, there is shown at 5 (Figs. 1 and 2) a portion of an automobile body having an opening 6 for the reception of a door 7, these parts being representative of any construction leaving a joint or crevice 8 to be sealed.

One form of windlace embodying the present invention is shown in Figs. 1 and 2 as having a body portion formed by an elongated filler strip, or core 9, preferably of a substantially continuous, generally cylindrical shape, as shown. One desirable material for such filler strip has been

found to be a good quality of commercial sponge rubber which may be readily molded into the desired shape and permanently retains a substantial degree of resilient softness adapted to closely conform to any surface against which it may be 5 pressed.

The body portion of the windlace comprises also an elongated cover strip 10 of textile fabric preferably conforming to the color of the surrounding surfaces, or ornamentally configured, as may 10 be desired. This cover strip is folded substantially around the filler strip 9, with its marginal edges, 11, 12, extended in parallel, overlapping relation to a substantial distance laterally from the filler strip, as shown, so as to form an attaching flange 15 of any suitable width, having its parts secured together by one or more of the means hereafter described.

Interposed between the fabric layers 11 and 12 of the attaching flange is a layer 13 of a good 20 quality of resilient rubber preferably applied as a fluid latex coating on the inner surfaces of the fabric layers 11 and 12 and extending inwardly therefrom partly between the cover fabric and the filler 9, as at 14. After vulcanization, this 25 rubber layer firmly unites the fabric layers 11 and 12 and is itself united to the filler 9, so as to form a thoroughly integral structure. Such rubber layer affords a relatively high degree of permanent resilience in the attaching flange itself, and as 30 between the latter and the filler strip or body of the windlace, for pressing the body portion against the structural surface on the side of the joint to be sealed opposite the side to which the attaching flange is secured, as indicated at 15, 35 Fig. 1. The flange is secured to the structure by any suitable fastening means such as the tacks 16. In this embodiment of the invention the fabric layers 11 and 12 and the interposed rubber layer 13 are so disposed with reference to the body 40 portion as to project radially and concentrically therefrom, as desirable in some applications.

In the manufacture of such a windlace, the said latex coating may be applied to the surface of the cover fabric by brush or roller, or other 45 suitable means, as well understood in the art, the fabric surfaces then being brought together and held in the desired relation with the filler strip 9 in the final position of the parts. In the useful application of the windlace, the attaching 50 flange is laid in flat and smooth condition against a surface on one side of the joint to be sealed and secured by tacks 16 which are readily driven therethrough into the supporting surface, as shown, and in any longitudinal spacing which 55

may be required to secure the windlace in place.

Another important principle of the present invention is embodied in the provision of a construction for the attaching flange which allows it to be resiliently extended or stretched in a longitudinal direction. This is accomplished by forming in the fabric layers of the attaching flange a series of longitudinally spaced pairs of slits 17, Fig. 2, extending inwardly from the marginal edges of the fabric adjacent the filler strip. The slits of each pair are arranged oppositely or in coincident relation in the fabric layers 11 and 12, respectively. They may be preformed in the fabric before assembly in the windlace, or, in the embodiments shown in Figs. 1-3, they may be cut therein while the latex layer 13 is still soft and tacky so that the latex on opposite sides of each slit will reunite with itself before vulcanization to maintain the longitudinal continuity of the resulting rubber layer.

This flange enables the windlace to be curved uninterruptedly around a corner or curved portion of a door opening or other joint, as shown in Fig. 2, the supporting flange being on the outside of the curve, as shown. The rubber layer stretches resiliently between the sides of the slits 17 which separate, as shown at 17a, and such yielding of the attaching flange allows the body portion of the windlace to be curved uninterruptedly in desired position, while the supporting strip remains in flat and smooth condition on the surface to which it is attached. The body portion thus serves, in effect, as the neutral axis of bending, with the tension in the flange which stretches to accommodate it. The construction thus obviates the sliding of the filler strip 9 in the cover fabric, or the cutting away of portions of the filler strip, or other expedients heretofore found necessary in prior windlace constructions for bending smoothly around angular or curved joints to be sealed.

In Fig. 3 is shown a somewhat modified construction of the windlace comprising the same parts, but with the fabric layers 11 and 12 and the rubber layer 13 arranged in a generally tangential relation to the body portion 9, as desirable in some installations, particularly where the surface to be engaged by the body portion is depressed below that to which the windlace is attached, or to increase the sealing pressure of the body portion, or meet other special conditions. This modification is assembled and applied in use as already described in connection with that shown in Fig. 1.

In Fig. 4 is shown a still further modification in which the filler strip 9 and cover fabric 10 are the same as those described in connection with the modification of Fig. 1 but in which the rubber layer, instead of being applied as a latex 60 coating to the inner surfaces of the cover fabric, is in the form of two preformed sheets of rubber, 18 and 19, which are interposed between the fabric layers 11 and 12 of the supporting flange and extended part way between the filler strip 9 and the cover, as at 20. These rubber sheets are preferably caused to adhere to each other, the cover fabric, and the filler strip 9, by the application of a cement or solvent of any known or suitable variety, as well understood in the art, and, in addition, the fabric and rubber layers of the attaching flange may be secured together by a line of stitches 21 parallel with the filler strip 9. Such stitching, of course, may be employed also in the modifications of Figs. 1 and 3, if desired, to more securely unite the parts. In this em-

bodiment, the attaching flange is disposed radially and concentrically of the filler strip as in the modification of Fig. 1, but it may, of course, be arranged instead in the tangential position illustrated in Fig. 3. It is to be understood, of course, that the slitting of the attaching flange, as described in connection with the modification of Fig. 1, may also be employed in the constructions of Figs. 3 and 4, as actually indicated in Fig. 4 by the location of the sectional view at one of such 10 slits.

It will thus be seen that the invention accomplishes the objects stated above. The body portion is of a soft, resilient material adapted to conform in close sealing contact with one side of the 15 joint to be closed. The rubber layer of the attaching flange affords a high degree of resilience for holding the body portion of the windlace in sealing position, and the characteristics of this rubber material are of a nature to maintain such 20 resilience with substantial permanency. The provision of a longitudinally resilient attaching flange facilitates even and uninterrupted application of the body portion in the desired sealing position, and smooth and flat attachment of the 25 flange to the supporting surface, in a unitary construction and association of the parts which can be quickly and conveniently applied in use.

The invention has been herein disclosed by way of illustration, in several embodiments thereof, 30 and it is further contemplated that other modifications of the construction and arrangement of parts may be employed within the scope of the appended claims.

We claim:

1. A windlace comprising a flexible elongated filler strip, a strip of fabric folded around said filler strip with its marginal edges extending laterally from said filler strip to provide an attaching flange, and a layer of resilient rubber interposed between the fabric layers of said flange and united thereto and with said filler strip, said rubber layer being continuous but the fabric layers of said flange having spaced coincident slits extending inwardly from the edges thereof toward 45 said filler strip so that said flange may be resiliently extended longitudinally to accommodate bending of said filler strip.

2. A windlace comprising an elongated flexible filler strip, a fabric cover enclosing said strip and 50 having its marginal edges extended laterally thereto to form an attaching flange, and a layer of resilient rubber interposed between the fabric layers of said flange and united therewith and with said filler strip to provide in said flange a 55 unitary resilient support for said strip, said rubber layer being substantially continuous longitudinally of said strip but the fabric layers of said flange having longitudinally spaced pairs of oppositely arranged slits extending inwardly from the edges 60 thereof toward said strip for resilient longitudinal extension of said flange during bending of said filler strip.

3. A windlace comprising an elongated filler strip of relatively flexible soft material, an elongated cover strip of textile fabric extended around said filler strip and having its marginal portions extending laterally from said filler strip to provide an attaching flange and a substantially flat layer of resilient rubber interposed between the 70 fabric layers of said flange and vulcanized thereto and to said filler strip to render said flange resilient and integral with said filler strip, said rubber layer being substantially continuous longitudinally of said strip but the fabric layers of said flange 75

being formed with pairs of opposite slits extending inwardly from the edges thereof toward said filler strip to permit stretching of said rubber layer at said slits to accommodate bending of said filler strip.

4. A windlace comprising an elongated filler strip of sponge rubber, a cover strip of textile fabric folded around said strip with its marginal edges extending in overlapping relation laterally from said strip, and a layer of resilient rubber interposed between the edges of said fabric and vul-

canized thereto and to said filler strip to provide an integral resilient attaching flange, said rubber layer being substantially continuous longitudinally of said filler strip but the fabric layers of said flange having spaced longitudinally thereof a series of pairs of opposite slits extending inwardly from the edges thereof toward said filler to provide for resilient extension of said flange to accommodate bending of said filler strip.
